UNITED STATES PATENT OFFICE.

ULRICH KOHLER, OF BERN, SWITZERLAND, ASSIGNOR TO HASLER A.-G. VORMALS TELEGRAPHENWERKSTÄTTE VON G. HASLER, OF BERN, SWITZERLAND, A SWISS CORPORATION.

INKING MECHANISM OF MACHINES FOR FRANKING POSTAL MATTER AND THE LIKE.

Application filed September 8, 1926, Serial No. 184,213, and in Switzerland September 16, 1925.

My invention relates to machines for franking postal matter and the like by means of dies or stamps, and has for its object to provide inking mechanism of improved construction for the same.

According to the invention the inking mechanism comprises a frame work removably inserted in the housing of the franking machine, on which frame work is removably mounted an ink box with doctor roll, under which box is guided a frame that carries the inking roll and is reciprocated by a lever which is positively connected to it and actuated by the driving mechanism of the franking machine, the displacement of which frame in the one direction feeds the doctor roll of the ink box step-by-step.

According to another feature of the invention there is removably accommodated in the ink box an ink container which is closed above by an ink-loading beam and below by the doctor roll and, after removal from the ink box, can be taken apart for cleaning purposes.

Conveniently, a rotating intermediate roller is arranged between the inking roll and the doctor roll, from which latter ink is transferred to the intermediate roller by a lick roller that swings to and fro between the same, which swinging movement is derived from the said reciprocating frame driven by means of a cam which in its starting position holds said frame in such a position that the lick roller and inking roll are free.

Preferably, a forked lever engages the said frame carrying the inking roll, and a second lever is fast on its shaft beside a rotary cam, which second lever is actuated in the one direction by a crank pin on the cam and in the other direction by the cam portion of the cam.

A further feature of the invention resides in the said lick roller being mounted on a vertically swinging plate which carries a yielding lever within the range of a tappet arranged on said reciprocating frame, by means of which lever the plate with the lick roller is moved up and down when the frame reciprocates.

Conveniently, one bearing of the lick roller and the inking roll are each movable laterally in order to remove these rolls.

Yet another feature of the invention is a

pawl which engages with a ratchet wheel on the doctor roll, and is so operatively connected with the reciprocating frame that it is driven by the frame only during a portion of its travel.

Conveniently, the pawl is mounted on a lever which is under the control of a spring tending to retract it and press it against the ratchet wheel of the doctor roll, the stroke of which lever can be regulated by another adjustable lever serving as a stop.

An embodiment of the invention is diagrammatically illustrated by way of example in the accompanying drawing, wherein:—

Figure 1 is a vertical section through one form of inking mechanism according to the invention,

Figure 2 is a plan view thereof,

Figure 3 is a side elevation of the feed device of the doctor roll, while

Figures 4, 5, 6, 7 and 8 show details.

According to the drawing, the inking mechanism forming the subject-matter of this invention is removably mounted in the casing 1 of a franking machine provided with a die or stamp wheel 2, and is carried by a horizontal plate 4 adjustable in height by means of screws 3. This inking mechanism comprises a framework having two vertical side plates 5 rigidly connected together by cross bars 6.

A yoke-shaped frame 8 is longitudinally slidable in horizontal grooves 7 formed in the inner faces of the side plates 5. The free ends of the limbs of this frame face the die wheel 2 and removably carry an inking roll 9 which serves for applying ink to the lower dies of the wheel 2. The roll 9 can be set at the correct height by an adjustment of the plate 4.

A forked lever 11, whose shaft 12 carries a second lever 13, engages from underneath a cross bar 10 in the rear part of the frame 8. A cam 15 which carries a laterally projecting pin 16 is mounted beside said lever 13 on a shaft 14 driven positively by the driving mechanism of the franking machine. When the cam 15 rotates in the direction of the arrow the pin 16 carrying an antifriction roller strikes the broader end 13' of the lever 13, whereby this lever with the shaft 12 and lever 11 moves out of a position situated a little behind its position shown in full lines into the position indicated by

broken lines. The lever 11 moves the frame 8 from its rear to its front position indicated in broken lines, in which position the roll 9 rolls over the die of the wheel 2 to be used, thereby inking the face of the same.

The cam 15 has in its periphery a recess 17, into which enters an antifriction roller 18, carried by the lever 13 and generally bearing on the periphery of the cam, in the initial position of the roller 18, so that the frame 8 is situated not quite in its rear end position and the roll 9 is out of contact with an intermediate roller 19 of metal. An impression in the form of a longitudinal groove is thereby prevented from being produced in the roll 9 of elastic material owing to its lying for a long time against the intermediate roller 19 when the franking machine is at rest.

The two side plates 5 are provided each with a recess 20, in which an ink box is removably inserted. This box comprises a casing 21 that is U shaped in horizontal section, and the side walls of which are connected together above by a cross bar 22. In this casing 21 is removably inserted an ink container comprising three fixed side walls 23 and a front wall 26 that is slidable in vertical grooves 24 and can be removed upwards by means of a lug 25. The ink container rests below on two pins 27 extending forwardly from the rear wall of the box 21, and is closed below by a doctor roll 28 journaled in the two side walls of the box 21, and above by a vertically movable loading beam 29 slidingly fitting in the ink container. This beam 29 rests on the ink in the container, protects the ink from dust and oxidation and presses it down by its own weight. The rear wall of the ink container is pressed lightly against the doctor roll 28 by two screws 30 in the rear wall of the box 21, so that when the roll 28 is rotated, only quite a thin film of ink is applied to its periphery.

The doctor roll 28 is rotated step-by-step by the frame 8 by means of the device illustrated in Figure 3. Roll 28 carries at its one end a ratchet wheel 31 with which a pawl 32 having several teeth engages. The pawl 32 has its rear end pivoted to a two-armed lever 33 and is held in engagement with the ratchet-wheel 31 and pulled towards the rear by a spring 35 detachably attached to it at 34. The length of the stroke of the pawl 32 can be regulated by a lever 37 which is rotatable about the pivot-pin 36 of the lever 33 and is adjustable by means of a snap catch on a toothed rack 38 of one side plate 5. The lever 33 has a lug 39 which overlies the lever 37 which when bearing against the lever 33 limits the rear end position of the pawl 32. This pawl has at its front end a stop 40 depending within reach of a nose 41 on the frame 8. When

this frame has almost reached its front end position, the nose 41 hits against the stop 40 and drives the pawl 32 into its front end position. When the frame 8 moves backwards the pawl 32 is pulled back by the spring 33 without, however, driving the doctor roll 28. When the lug 39 strikes the lever 37 the rearward movement of the pawl 32 ceases. It will be seen that according to the position of the lever 37 the lug 39 will abut against it sooner or later, so that the rear end position of the pawl is situated forwards or backwards, and consequently the nose 41 hits the stop 40 later or earlier and moves it a smaller or greater distance. Consequently, the pawl 32 can turn the doctor roll about a smaller or greater angle.

The ink is transferred from the doctor roll 28 to the intermediate roller 19 by means of a lick roller 43 consisting of elastic material, the roller 19 being rotated by a spur gear 42 (Fig. 2) when the franking machine is working. One end pivot of the roller 43 is journaled in an eye 44 in a plate 45 (Figs. 1, 4 and 5) and its other end pivot is journaled in an eye 46 of a lever 47 which laterally embraces the one longitudinal edge of the plate 45 and can swing outwards (Fig. 5) about a pivot 48 against the action of a spring 49. When the lever 47 is swung upwards, one pivot of the roller 43 is released so that the latter can be easily removed for cleaning purposes.

The plate 45 can swing up and down about an axle 50 resting in the side plates 5, which axle can be withdrawn endwise in order to remove the plate 45 together with the lick roll 43 out of the framework 5, 6. The front arm of a cranked lever 53 pivoted at 52 lies in a longitudinal slot 51 in the plate 45. A spring 54 holds the lever 53 in such a position that its front arm extends its entire length beyond the bottom of the plate 45. The rocking movement of the lever 53 is limited by a set-screw 55 at its rear end. On the rear cross bar of the frame 8 is arranged a tappet 56 which, when the frame 8 reciprocates, slides along the bottom of the lever 53 and lifts it and the plate 45 so far that the lick roller is pressed yieldingly against the doctor roll 28. The tappet 56 is so dimensioned that it holds the lever 53 with the plate 45 in the position shown in full lines in Figure 1, in which position the antifriction roller 18 lies in the recess 17 in the cam 15, but only at such a height that the lick roller 43 contacts neither with the intermediate roller 19 nor with the doctor roll 28. Longitudinal grooves are thereby prevented from being formed by the roller 43 bearing for a long time on either of the said rolls 19 and 28 whilst the machine is idle.

The described mechanism operates as follows:—When the franking machine is

- driven the cam 15 and intermediate roller 19 rotate. When the antifriction roller 18 leaves the recess 17 the frame 8 makes a small rearward movement, whereby the lick-
 5 roller 43 and the inking roll 9 contact with the intermediate roller 19. When the pin 16 strikes the face 13' of the lever 13 a rapid forward movement is imparted to the frame 8, whereby the lick roller 43 is pressed
 10 against the doctor roll 28 and the inking roll 9 is rolled under the die or stamp situated in the operative position and inks the same. Shortly before the frame 8 reaches its front end position, the nose 41 strikes
 15 the stop 40 of the pawl 32 and drives the latter, whereby the doctor roll 28 is fed one step forward. When the pin 16 leaves the face 13' that portion of the cam of smallest diameter meets the antifriction roller
 20 18, and in consequence of the rapid change from minimum to maximum diameter of the cam rapidly returns the levers 13 and 11 with the frame 8, until the intermediate roller 19 contacts with the inking roll 9. As
 25 soon as the tappet 56 leaves the lever 53 the plate 45 descends with the lick roller 43, so that the latter comes into contact with the intermediate roller 19 and transfers ink to it. When the antifriction roll 18 enters into the
 30 recess 17 in the cam 15 the ink roll 9 is moved away from the intermediate roller 19 and the lick roller 43 is removed from the latter. The described cycle of operations is repeated before each letter, card or the
 35 like is stamped or otherwise marked by the machine.
- When the cover 1 is removed the entire inking mechanism, with the exception of the operating members 11, 12, 13, 14 and 15, can be removed and one can test it outside the machine as to its operation by moving the frame 8 to and fro. For cleaning the inking mechanism the ink box 21 with its ink container can be lifted out of the frame 5,
 40 6 and the ink container 23, 26 can be removed from the ink box and be taken apart. Then the plate 45 with the lick roller can be removed, and the latter can be taken out of its bearings by swinging the lever 46. In
 45 order to be able to remove the inking roll 9 for conveniently cleaning it, its one pivot 9' (Fig. 6) is held in a recess 8' of the frame 8 by a leaf spring 8'' which can be turned upwards about a pivot pin 8''' and bent outwards.
- I claim:—
1. Inking mechanism comprising in combination a framework adapted to be detachably inserted in a machine, an ink box removably mounted on said framework, an ink container open at the top and bottom removably inserted in said ink box, a doctor roll journaled in said ink box closing the open bottom of said ink container, a sliding member fitting the open top of said ink container, a frame mounted to reciprocate below said box, an inking roll carried by said frame in operative relation to said doctor roll, a lever arranged to reciprocate said frame, and a feed mechanism actuated by said frame and arranged to feed said doctor roll step-by-step. 70
2. Inking mechanism comprising in combination a frame work adapted to be removably inserted in a machine, an ink box detachably carried by said frame work, an ink container adapted to be taken apart removably accommodated in said ink box, and having an opening at the top and bottom, a doctor roll journaled in said box and arranged to close the bottom of said container, an ink-loading beam inserted into the top opening of said container, a frame mounted to reciprocate under said ink box, an inking roll carried by said frame in operative relation to said doctor roll, means for reciprocating said frame, and a feed mechanism actuated by said frame and arranged to intermittently rotate said doctor roll. 75
3. Inking mechanism comprising in combination a framework adapted to be removably inserted in a machine, an ink box having a doctor roll associated therewith removably mounted on said framework, a frame mounted to reciprocate below said ink box, an inking roll carried by said frame, an intermediate roller arranged between said rolls, a lick roller mounted to swing between said doctor roll and said intermediate roller 80 for transferring ink to the latter, means comprising a cam for reciprocating said frame, feed mechanism actuated by said frame and arranged intermittently to rotate said doctor roll, an oscillating means actuated by said frame and arranged to swing said lick roll to and fro between said doctor roll and intermediate roller, said cam in its starting position holding said frame in a position to keep said lick roller and inking roll free from said doctor roll and said intermediate roller. 85
4. Inking mechanism comprising in combination a framework adapted to be removably inserted in a machine, an ink-box having a doctor roll associated therewith removably mounted on said framework, a frame adapted to reciprocate under said ink-box, an inking-roll carried by said frame in operative relation to said doctor roll, a shaft, a forked lever fast on said shaft and engaging said frame, a second lever fast on said shaft, a rotary cam having a crank pin arranged to rock said second lever in one direction, a shaped portion of said cam being arranged to rock said second lever in the other direction and thereby reciprocating said frame, a pin carried by said second lever so as to bear on the periphery of said cam to normally hold said frame away from 90
- 105
- 110
- 115
- 120
- 125
- 130

its extreme rear position, and a feed mechanism actuated by said frame and arranged intermittently to rotate said doctor roll.

5. Inking mechanism as set forth in claim 3, wherein one bearing each of the lick roller and inking roll are movable laterally in order to remove these rolls.

6. Inking mechanism as set forth in claim 3, comprising a vertically swinging plate carrying said lick roller, a spring controlled lever mounted on said plate, and a tappet carried by said frame arranged to coact with said lever and thereby reciprocating said plate and lick roller upon said frame being reciprocated.

7. Inking mechanism comprising in combination a framework adapted to be removably inserted in a machine, an ink-box removably mounted on said framework, an ink container open at the top and bottom removably inserted in said ink box, a doctor roll journaled in said ink box closing the open bottom of said ink container, a sliding member fitting the open top of said ink container, a frame mounted to reciprocate be-

low said box and roll, an inking roll carried by said frame in operative relation to said doctor roll, means for reciprocating said frame, and a pawl-and-ratchet feed mechanism actuated by said frame and arranged intermittently to rotate said doctor roll, said feed mechanism comprising a ratchet wheel arranged to drive said doctor roll, and a pawl engaging said ratchet wheel and operatively connected with said frame, so as to be driven by the latter only during a portion of its travel.

8. Inking mechanism as set forth in claim 7, wherein said pawl is mounted on a lever controlled by a spring tending to retract it and press it against said ratchet wheel, and a second adjustable lever constituting a stop is arranged to regulate the stroke of the first said lever.

In testimony whereof I affix my signature.

Signed at Bern, Switzerland, this twenty-seventh day of August 1926.

ULRICH KOHLER.
